UNITED STATES PATENT OFFICE.

EARL D. RADER, OF BEDFORD TOWNSHIP, WESTCHESTER COUNTY, NEW YORK, AS-
SIGNOR TO DEXTER FOLDER COMPANY, OF NEW YORK, N. Y., A CORPORATION OF
NEW YORK.

SAMPLE FOLDER FORM.

Application filed January 20, 1922. Serial No. 530,561.

Sample forms have heretofore been provided to assist operators, lay-out men and others in preparing the required forms and impositions for folding upon certain machines to obtain the desired result in folded, printed products. These sample folder forms have been commonly used in connection with simple jobbing folding machines, which turn out single folded sheet products. It has not, however, heretofore been possible to produce satisfactory sample folder forms for machines of the double-16, quadruple 16 and double-32 folder types, first, because a one-part or single sheet folded form cannot be arranged to accurately represent the two-part or four-part folded sheet products of such machines, and second, the making of such forms in two or more parts corresponding with such products has heretofore been unsatisfactory because there has been no provision for preserving the identity and relationship between the severed folded parts of the forms. Without some identifying means, it is practically impossible to accurately assemble the severed parts of such forms to represent the whole form, and in the presence of a large number of such two-part and four-part forms, there is great danger of hopeless confusion. The object of the present invention is to overcome this difficulty by producing sample folded dummy signature forms for the double-16, quadruple-16 or double-32 folding machines, which are provided with properly related key markings so that after the sample form is folded and separated into parts, the parts can be readily associated in their original relation to indicate the desired impositions for producing the folded, printed product. In addition to the specified key marking for indicating the association and relationship of the parts of a form, I propose to include upon the sample forms the necessary instructions for the manipulation and gaging of the sheet to obtain the desired folded products in the double-16, the quadruple-16 or the double-32 folding machines.

In order that my invention may be fully understood, it will first be described with reference to the accompanying drawing and afterwards more particularly pointed out in the annexed claims.

In said drawings:

Fig. 1 is a face view of a two-part sample form embodying my invention.

Fig. 2 is a similar view of the reverse side of said sample form.

Fig. 3 is a face view of the two-part form after the first fold.

Figs. 4 and 5 are respectively face views 60 of the two parts of the form after the second fold.

Fig. 6 is a face view of the superimposed completely folded two parts of the form.

Figs. 7 and 8 are respectively a longitudinal sectional view and a transverse sectional view of the superimposed, twice folded parts of the form.

Fig. 9 is a face view of a modified two-part sample folder form embodying my invention. 70

Fig. 10 is a reverse view of the same on a smaller scale.

Fig. 11 is a face view of the same two-part form after it has received the first fold. 75

Figs. 12 and 13 are views of the respective parts of the same folded form at the next stage in which the part shown in Fig. 12 has been tipped through the second fold rollers without being folded, while the part shown in Fig. 13 has received its second fold. 80

Figs. 14 and 15 are views of the parts shown respectively in Figs. 12 and 13 after the final fold, the part shown in Fig. 14 having received a second fold by the third fold rollers, while the part shown in Fig. 15 has received the third fold. 85

Fig. 16 is a face view of the same two form parts, the part of Fig. 14 being partially inserted in the part of Fig. 15. 90

Fig. 17 is a transverse, sectional view of the same two form parts in inserted position.

Figs. 18 and 19 are respectively a face view and a reverse view of a four-part form embodying my invention. 95

Figs. 20 and 21 are respectively a face view and a reverse view of another four-part form embodying my invention.

In Figs. 1 to 8 of the drawings, I have shown a simple two-part form for producing two signatures of eight pages each, which signatures may consist of like pages each numbered from 1 to 8, or of continuous pages numbered from 1 to 16. 100

In Fig. 1 the outside or face view of the double form is represented. On one portion of this face of the form is printed a schedule of maximum and minimum sizes of sheets both flat and folded to indicate the possible products. On the other portion of said 105 110

form is given a scale of exact sheet sizes both when flat and folded. This front face of the two-part form indicates the relation and numbering of pages for the production 5 of either two duplicate signatures with like numbered pages, or two different signatures with successively numbered pages. Each of these form parts is also provided with a key number, which in the particular form illustrated 10 is the numeral 1; but it will be understood that any arbitrary symbol may be used to indicate that the two parts belong to the same form.

In Fig. 2, I have shown the reverse face 15 of the same two-part form as shown in Fig. 1. Upon this reverse face is printed near one edge the words "Folder guide" and adjacent thereto the instructions "This side up when laid on folder", indicating the proper 20 presentation in the folding machine of a sheet made up on this form. This reverse face of the two-part form also contains adjacent to its side edges the words "Folder gripper" and adjacent to one side the words 25 "This gripper is preferable", indicating that experience under commercial conditions has shown that the indicated edge of the sheet is better for registering purposes. This reverse face of the form also contains indications 30 of the form impositions including page numberings, both for the production of two like page signatures or for two different signatures with successive page arrangement. This face of the form also indicates 35 the line upon which the sheet is folded and cut in two as it passes through the first fold mechanism. The inner face of the two-part form as shown in Fig. 2 contains a large key marking in the form of the numeral 1 printed 40 across the line upon which the form is divided in two parts, so that one part of the key numeral will be on one part of the form and the other on the other part.

Fig. 3 represents the two-part form of 45 Fig. 2 after it has passed through the first fold rollers. The exposed faces of the two parts of the form have "second fold" line indications and the page impositions.

Figs. 4 and 5 show the two parts of the 50 form respectively, after the second fold. In these figures the individual key numbers "1" are exposed as well as the dual page numbering. These figures correspond with parts of the face illustrated in Fig. 1.

In Fig. 6 the two parts of the completely 55 folded form are represented in superimposed position, and in Figs. 7 and 8 these superimposed parts are represented in section.

In Figs. 9 to 17, both inclusive, I have 60 shown a more complicated dummy form embodying my invention. This form is one designed for a standard double-16 or double-32 folder for producing twenty-four page signatures made up of sixteen pages produced

70 by three right angle folds of two-thirds of a sheet, and eight pages made up by two parallel folds in the remaining one-third of the sheet, the eight page portion being inserted within the sixteen page portion.

Fig. 9 represents the outer face view of the two-part form, which is divided into two portions, one of which is twice as large as the other. The two portions have printed upon them key markings which in the particular form is the numeral "3". One portion is provided with scales showing the maximum and minimum sizes of sheets both flat and folded, and showing the variations 75 in the sizes of sheets both flat and folded. 80 Both parts of the form indicate the impositions by arrangement of page numbers and also the "second fold" and "third fold" lines. This face of the form also gives the "perforation" line on the larger portion of the sheet coincident with the "second fold" line and on the smaller portion instructions "Tip 85 this edge through second fold rollers without folding,—tip in device required". The smaller portion of this form also includes 90 under the "second fold" indication the words "(Made at third fold)" and with an arrow pointing to the final fold line the words "Inserts mechanically".

Fig. 10 is a view of the reverse side of the 95 form shown in Fig. 9, this figure being on a smaller scale. This figure indicates the "folder guide" edge of the sheet and the "folder gripper" edges of the sheet with specific instructions regarding the two edges. 100 This view also shows the line upon which the "sheet cuts in folder" and the line "perforation". Extending across the line of separation between the larger and smaller portions of this form in Fig. 10 is a large key 105 numeral "3", part of the number being on each portion of the form to indicate the proper relationship of the two parts.

In Fig. 11 the two parts of the form shown 110 in Fig. 10 are represented after they have passed through the "first fold" rollers, the form impositions of the exposed faces of the form being properly represented as well as the "second fold" line of the larger portion and the "second fold",—"made at third fold)" of the smaller form. The smaller form also contains the instructions "Tip this edge through second fold rollers without folding,—tip in device required."

Fig. 12 is a face view of the smaller portion 115 of the double form after it has been tipped through the "second fold" rollers. This view is identical with the left-hand portion shown in Fig. 11.

Fig. 13 shows the larger portion of the 120 form after it has passed through the "second fold" rollers, this view indicating the line of "third fold".

Figs. 14 and 15 are respectively the smaller 125 and larger portions of the form after they

have passed the "third fold" rollers, the part shown in Fig. 14 having two parallel folds forming eight pages, while the part shown in Fig. 15 has three right angle folds to 5 form sixteen pages.

Figs. 16 and 17 are intended to indicate the inserted relation of the part of Fig. 14 within the part of Fig. 15, the finished product being the twenty-four page signature. 10

In Figs. 18 and 19, I have shown the face and reverse views of a further modification and extension of my present invention, this 15 illustration representing a four-part dummy form for the production of sixteen page signatures by two parallel folds and one right angle fold on a quadruple-16 or double-32 folding machine. The imposition indicated on Figs. 18 and 19 shows page numbering 20 for producing four signatures of like pages numbered from 1 to 16, or four signatures of continuous pages numbered from 1 to 64. It is intended that these four-part dummy 25 forms shall include the necessary instructions and indications, such as indicated in the illustrations of the preceding figures of the drawings. These details will not be dwelt upon since Figs. 18 and 19 are mainly 30 to illustrate the application of the invention to a four-part dummy form. It will be noticed in Fig. 18 that the four sections of the form are indicated by the characters 2, 2^A, 2^B and 2^C, all the parts including the key numeral "2". On the reverse face shown 35 in Fig. 19, it will be observed that the key numeral "2^A" is printed across the line of separation between sections "2" and "2^A", while the key numeral "2^B" is printed across the line separating "2^A" and "2^B" and the key 40 numeral "2^C" is printed across the line of separation between "2^B" and "2^C". The marking of the four parts of the dummy form serves to clearly indicate the proper 45 association and arrangement of the parts for accomplishing the desired result.

In Figs. 20 and 21, I have shown a further example of a four-part dummy form embodying my invention. This form illustrates the imposition for producing thirty- 50 two page signatures, either in the form of two signatures of like pages numbered from 1 to 32, or two signatures of continuous pages numbered from 1 to 64. On the face of the four-part form shown in Fig. 20, two 55 of the form parts have key numerals "4^A", while the other two have key numerals "4^B", the numeral "4" being common to the whole set. In Fig. 21 the reverse face of this four part form is illustrated with large key numerals "4" extending across the three lines of separation between the form parts in 60 several transverse zones, so as to indicate accurately the correlation of the parts to

make up a proper form. This dummy form of Figs. 20 and 21 is also intended to include the necessary instructions and other indications referred to in the two-part form hereinbefore described. 65

It should be understood that there are great numbers of form arrangements for 70 producing various folded signatures, many of which products are produced on the double-16, the quadruple-16 or double-32 folding machines. The arrangement of key characters upon the parts of all forms having two or more parts, whereby the related parts can be properly identified and placed in position to accurately indicate the required impositions for producing such product is the essential feature of my invention. 75 In addition to this main feature, I prefer to so arrange the key characters that the characters will be printed partly on one piece and partly on another piece of a divided form, so that the proper arrangement 80 will be indicated by piecing together the parts of the key character. I have found it most convenient to arrange the improved sample forms as miniature dummies, but the invention is not limited to this embodiment. 85

I claim:—

1. A plural-part dummy signature, each of the parts of which is individually folded like the corresponding part of the finished signature, and each part is marked with a 95 common key character to indicate the original imposition and sheet arrangement of dummy parts.

2. A dummy signature comprising a plurality of separated individually folded sheet 100 parts having marked thereon complementary portions of a key character which is divided on the line of separation between said parts.

3. A divided sheet dummy signature comprising a plurality of separated sheet-parts which have fold line indications upon their faces in position of desired folds, printed imposition instructions upon one of said dummy parts, and a divided key character 105 printed partly on each dummy part and divided on the line of separation between the parts.

4. A dummy signature comprising a plurality of separated sheet-parts having fold 115 line indications arranged in the desired locations upon said parts, printing imposition and folding instructions printed upon one of said parts, a common key character marked upon each of said parts, and a divided key 120 character printed upon continuous surfaces of adjacent sheet-parts and divided by the line of separation between said adjacent parts.
